US0D1081582S

(12) **United States Design Patent** (10) **Patent No.:** **US D1,081,582 S**
(45) **Date of Patent:** **** Jul. 1, 2025**

(54) **ELECTRICAL SOCKET**

(71) Applicant: **Honeywell International Inc.**,

Charlotte, NC (US)

(72) Inventors: **Jun Liu**, Beijing (CN); **Qiang Peng**,
Shanghai (CN); **Hongjie Ji**, Tianjin (CN);
Wendy Guo, Tianjin (CN)

(73) Assignee: **HONEYWELL INTERNATIONAL INC.**, Charlotte, NC (US)

(**) Term: **15 Years**

(21) Appl. No.: **29/919,181**

(22) Filed: **Dec. 1, 2023**

(51) LOC (15) Cl. **13-03**

(52) U.S. Cl.

USPC **D13/139.1**; D13/152

(57) **CLAIM**

The ornamental design for an electrical socket as shown and described.

DESCRIPTION

FIG. 1 is a perspective view of an electrical socket;
FIG. 2 is a front elevational view of the electrical socket of FIG. 1;

FIG. 3 is a left side view of the electrical socket of FIG. 1;
FIG. 4 is a right side view of the electrical socket of FIG. 1;
FIG. 5 is a top side view of the electrical socket of FIG. 1;
FIG. 6 is a bottom side view of the electrical socket of FIG. 1;

FIG. 7 is a perspective view of another electrical socket;
FIG. 8 is a front elevational view of the electrical socket of FIG. 7;

FIG. 9 is a left side view of the electrical socket of FIG. 7;
FIG. 10 is a right side view of the electrical socket of FIG. 7;

FIG. 11 is a top side view of the electrical socket of FIG. 7;
and

FIG. 12 is a bottom side view of the electrical socket of FIG. 7.

FIG. 13 is a perspective view of yet another electrical socket; and,

FIG. 14 is a front elevational view of the electrical socket of FIG. 13.

The portions illustrated in broken lines on the figures form no part of the claimed design.

1 Claim, 14 Drawing Sheets
